UNITED STATES PATENT OFFICE.

GREENBERRY BORING, OF JOHNSON CITY, TENNESSEE.

VALVE-GRINDING APPARATUS.

1,362,469.

Specification of Letters Patent. Patented Dec. 14, 1920.

Application filed April 10, 1920. Serial No. 372,793.

To all whom it may concern:

Be it known that I, GREENBERRY BORING, a citizen of the United States, residing at Johnson City, in the county of Washington and State of Tennessee, have invented certain new and useful Improvements in Valve-Grinding Apparatus; and I do hereby declare the following to be a full, clear, and exact description of the invention, such as will enable others skilled in the art to which it appertains to make and use the same.

This invention relates to valve grinding mechanisms, especially adapted for use in simultaneously grinding the several valves of an internal combustion engine.

An object of the invention is to produce a mechanically operated grinding apparatus which can be easily installed in garages, repair shops, factories and the like, for effectively grinding all of the valves of an automobile engine at one and the same time, without dismantling the engine to any material extent.

Another object of the invention is the production of a valve grinder having a plurality of grinding units or stations, any one of which can be independently cut out without interfering with the continued grinding operations of the others.

A further object of the invention is to produce a valve grinding mechanism in which the grinding units are successively oscillated and periodically advanced so as to insure a uniform grinding of the valve upon its seat.

With these and other objects in view the invention further consists in the provision of a comparatively light, durable and inexpensive arrangement of the several parts hereinafter described and pointed out in the appended claims.

In the accompanying drawings illustrating an embodiment of my invention, and in which corresponding reference characters designate similar parts in the several views:

Figure 1 is a plan view of the grinding mechanism;

Fig. 2 is a vertical, transverse, sectional elevation showing one of the grinding units in an inoperative or disengaged position;

Fig. 3 is an enlarged fragmentary plan of one of the grinding units;

Fig. 4 is an enlarged vertical sectional view through one of the grinding units in an operative grinding position;

Fig. 5 is a detail horizontal sectional view on the line 5—5 of Fig. 4; and

Fig. 6 is a detail vertical sectional view through the releasing mechanism for effecting the advance or successive change in the oscillations for uniformly grinding the valve.

The present invention, generally stated, includes among other things, a frame having mounted therein a series of grinding units 65 preferably arranged in groups of two to correspond with the relative location of the valves in the head of each cylinder of a multi-cylinder explosive type of engine, means for positively imparting grinding 70 movement to each unit, means for successively changing the path of travel or oscillation of each grinding unit, and means for independently releasing or disconnecting any one or more of the grinding units during the operation of the device.

Referring to the drawings, the main frame 1 is of rectangular contour, and is designed to support the several grinding units or stations 2. The grinding units 2 are further supported in a supplemental frame 3 formed by upper and lower bar 4 and 5 suitably connected with the main frame 1.

Each grinding unit is operatively connected to a driving means consisting of a cam 85 shaft 6, mounted in bearings 7, secured to the frame 1, and a pulley or other device 8 secured to one end of the shaft for receiving power from any convenient source, not shown.

A series of cams 9, angularly disposed with relation to each other upon the shaft 6, are shown, said cams being designed to actuate rods 10 interconnected with their respective grinding units. The latter being of the same general construction, a description of but one will suffice.

Referring particularly to Figs. 3 to 6, the unit 2 includes a grinding element 11 consisting of a shaft 12 having on its lower end a suitable valve or grinder engaging head 13, and upon its upper end a toothed wheel 14. The extreme upper end 15 of the shaft 12 is journaled or telescoped into the lower end 16 of an interconnected shaft 17, 105 which latter has its upper end journaled in the upper cross bar 4 of the supplemental frame.

Secured to and extending from the shaft 17 is an arm 18, the end of which is con-

nected at 19 to a movable yoke 20 which in turn is interconnected with the actuating rod 10 hereinbefore referred to.

The yoke 20 is provided with an open 5 collar 21 at the end opposite to the pivotal connection 19, so as to permit of its being raised out of operative connection, as shown in Fig. 2. Spring actuated fingers or catches 22 are arranged in each side bar of the yoke, 10 for retaining the tapered end 23 of a relatively short link 24 pivotally connected at 25 to one end of the actuating rod 11. Each finger or catch 22 is provided with a tapered or cam nose 26 capable of co-acting 15 with the tapered head 23 in effecting an engagement of the yoke with the actuating rod 11. The yoke is angularly movable with respect to the actuating rod 11, which as shown is slidingly supported in a frame 20 27. A spring 28 is interposed between one end of the frame 27 and a collar 29 secured to the rod 11. The rod 11 is preferably provided with an enlarged head 30 designed to bear against and receive motion from the 25 cam 9, the spring 28 serving to hold the head 30 against the cam as will be understood.

Extending from the yoke 20 is a finger or pawl 31 provided with a hooked end 32 arranged to engage the teeth of a ratchet 33, 30 keyed upon a shaft 34 which in turn is journaled in bearings 35 extending from the main frame 1.

Upon each reciprocation of the rod 11 and 35 interconnected yoke 20, the finger or pawl 31 successively engages the teeth of the ratchet 33 thereby rotating the shaft 34.

Secured to the shaft 34 is a cam 36 having oppositely disposed high portions 37 40 arranged to engage the end of an arm 38 for operating the valve changing or advancing mechanism now to be described.

The head 16 of the upper shaft 17 of the grinding unit is designed to support oppositely disposed pawls 39 provided with springs 40 for normally keeping the said pawls in engagement with the toothed wheel 14 heretofore referred to and a collar 41 is mounted upon the lower element or shaft 12 45 of the grinding unit, and has protruding therefrom an arm 42, the end of which is connected at 43 to the arm 38, which latter, as shown, is supported in a guide frame 44, and is provided with a spring 45 for keeping the end of said arm into operative engagement with the cam 36.

Oppositely disposed lugs 47 are provided on the collar 41, as best shown in Figs. 4 and 6, and are designed to disengage the 60 pawls 39 in a manner to be presently described in connection with the operation of the device.

The means for disengaging the grinding units comprises a lever 48 pivoted at 49 to 65 the frame 1. One end of the lever 48 is

bifurcated as shown, at 50, and is arranged to straddle and engage a collar 51 secured to the shaft 12. The other end of the lever is provided with a handle portion 52 which can be grasped by an operative and pressed downwardly for disengaging the grinding unit. A suitable latch 53 may be provided to hold the lever in elevated position. The spring 54 interposed between the upper bar 4 of the frame 3 and a collar 55 on the shaft 75 17 serves to return the grinding unit to its operative position.

In operation, the several grinding units 2 are arranged to receive simultaneous motion from the cams 9 provided on the shaft 6. 80 and as the actuating rods 10 are actuated, the interconnected yokes 20 reciprocate thereby imparting oscillatory movement throughout the arm 18 to the upper shaft 17 which is normally arranged to positively 85 engage and operate the shaft 12 carrying the grinding element engaging head 13.

Upon each reciprocation of the yoke 20 the pawl 31 operates to revolve the ratchet 33 which in turn rotates the shaft 34 upon 90 which is secured the cam 36. As the cam 36 moves through each one half revolution it will be seen that the arm 38 is caused to gradually move thereby bringing one of the lugs 47 under a pawl 39 causing the same 95 to disengage from the toothed wheel 14. The disengagement of this pawl permits the shaft 17 to continue its oscillations through its yoke connections, but in such a manner as to leave the shaft 12 stationary during 100 the return movement until the arm 38 has ridden off of the high point 37 of the cam 36. When the arm 38 moves to the lower portion of the cam, the lug 47 is released from the pawl 39 and the two shafts 17 and 12 respectively, are operatively connected so as to move in unison. During this change or advance of the grinding element, the other pawl 39 rides over the toothed wheel 14 as 105 will be understood.

While I have shown this means of changing and advancing the grinding element, other means may be employed and I do not limit myself to the exact form shown herein.

In disconnecting any one of the units, 115 upon completing the grinding operation, the lever 48 is depressed, thereby lifting the unit together with the yoke 20 from the tapered head 23. When thus disengaged, the actuating rod 10 and the short link 24 are free to reciprocate without imparting movement to the grinding unit. When the lever 48 is released the grinding unit and more particularly the open collar 21 of the yoke, drops over the tapered head 23 and the reciprocation of the rod 10 soon causes the spring catches 22 to slip over and engage the head 23 as shown in Fig. 3.

The advantages incident to the use of my invention are especially pronounced in 130

garages and repair shops where a single operative can manipulate one or more of these devices and at the same time attend to other duties. When one or more of the valves 5 have been sufficiently ground, the grinding unit therefor can be readily disconnected by the operator and the others allowed to continue to grind until all of the valves are properly ground.

10 Various changes in the proportion and arrangement of the several parts may be made without departing from the spirit of my invention and I do not limit myself to the exact construction herein set forth.

15 I claim:

1. A cylinder valve grinding device comprising a plurality of valve grinding elements, a shaft connected to each of said elements, means for intermittently disengaging 20 said shafts from the valve grinding elements during the grinding operation, and means for completely disconnecting one or more grinding elements without affecting the aforesaid intermittent operation of the 25 remaining elements.

2. A cylinder valve grinding device comprising a plurality of valve grinding elements, means including interconnected shafts for oscillating said grinding elements 30 and means for disengaging one of said shafts for intermittently operating the grinding elements to change the path of travel of the aforesaid oscillations.

3. A cylinder valve grinding device comprising a plurality of grinding elements, means for oscillating said grinding elements and means for disengaging said grinding elements from the aforesaid oscillating means for changing the path of travel 35 thereof.

4. A cylinder valve grinding device comprising a plurality of grinding elements,

means for oscillating said grinding elements, means for disengaging said grinding elements from the aforesaid oscillating 45 means for changing the path of travel thereof, and means for completely disconnecting said grinding elements independently of each other from the aforesaid oscillating means.

5. A cylinder valve grinding device comprising a valve grinding element, a shaft connected to said element, means for intermittently disengaging said shaft from the valve grinding element and means for 55 imparting motion to said shaft.

6. A cylinder valve grinding device comprising a valve grinding element, a shaft connected to said element, means including a ratchet mechanism for intermittently disengaging said shaft from the valve grinding element, and means for imparting motion to said shaft.

7. A power driven cylinder valve grinding device comprising an oscillating valve 65 grinding element, and means for automatically changing the path of travel of said grinding element.

8. A multi-cylinder valve grinding device comprising a series of grinding elements, 70 means for simultaneously operating said elements, said means including a cam actuated rod, means for independently disconnecting said elements, said means including a detachable yoke interposed between 75 the aforesaid grinding elements and cam actuating rod, and a lever for effecting the aforesaid disengagement.

In testimony whereof I affix my signature in presence of two subscribing witnesses.
